UNITED STATES PATENT OFFICE.

JOHN C. EDWARDS AND WILLIAM F. BOSSERT, OF UTICA, NEW YORK, ASSIGNORS TO SIGNAL ACCESSORIES CORPORATION, OF UTICA, NEW YORK, A CORPORATION OF NEW YORK.

PIPE CARRIER FOR RAILWAY SIGNAL SYSTEMS.

Application filed April 10, 1925. Serial No. 22,034.

To all whom it may concern:

Be it known that we, JOHN C. EDWARDS and WILLIAM F. BOSSERT, citizens of the United States of America, both of Utica, in the county of Oneida, in the State of New York, have invented new and useful Improvements in Pipe Carriers for Railway Signal Systems, of which the following, taken in connection with the accompanying drawings, is a full, clear, and exact description.

This invention relates to hoods for pipe carriers as used more particularly in the operation of railway signals in which motion is transmitted from a tower or other station to more or less distant semaphores or signals through the medium of pipes or equivalent connections.

These pipes are usually supported in suitable carriers arranged at intervals along the track and provided with roller bearings to facilitate the reciprocal movement of the pipes in the carriers which are usually held in an upright position upon suitable supports.

The main object is to protect the carriers and more particularly the rollers and adjacent portions of the pipes against accumulations of ice, snow and other foreign matter which might interfere with the free operation of the pipes in their respective carriers and at the same time to enable the protective units to be easily and quickly installed upon the carriers without in any way interfering with the free operation of the pipes and rollers.

Other objects and uses relating to specific parts of the pipe carriers and protective means will be brought out in the following description.

In the drawings:

Figure 1 is a perspective view of portions of a plurality of pipe carriers and adjacent portions of some of the pipes mounted together with my improvement for protecting the movable parts of the carriers and adjacent portion of the pipes.

Figures 2 and 3 are enlarged transverse vertically sectional views taken respectively on lines 2-2, and 3-3, Figure 1.

Figure 4 is a perspective view of one of

the detached hoods for a single pipe carrier.

Figure 5 is a transverse, vertical, sectional view of a modified form of hood in which the top portions of the opposed halves are connected by a separate spring plate.

As illustrated, the pipe carriers comprise two or more upright brackets —1— mounted side by side upon suitable supporting rods —2— and held in place by hook shaped clamping bolts —3—, the supporting rods —2— being preferably tubular and mounted side by side upon suitable supporting brackets —4— which in turn are bolted or otherwise secured to a supporting bed —5— of concrete or other suitable material.

The upright brackets —1— are of similar construction and reversible upon the supporting rods —2— and are preferably arranged in pairs, those of each pair having their upper portions in sufficiently spaced relation lengthwise of the supporting rods —2— to receive a pipe —6— or equivalent operating member commonly used in the operation of railway signals from a distant tower or other station.

The upper portions of the brackets —1— of each pair are provided with lengthwise slots —7— for receiving the reduced ends —8'— of a roller bearing —8—, said slots being elongated in the direction of length of the pipes —6— to permit the reduced ends or trunnions —8'— of a roller —8— to roll along and upon the lower walls thereof.

These rollers —8— are provided with peripheral annular grooves to form bearings for the pipes —6— to rest upon the upper faces of the rollers.

The brackets —1— of each pair extend upwardly at opposite sides of and some distance above the adjacent portions of the pipe —6— and are provided at their upper ends with upright slots —9— for receiving the opposite ends of a shaft —11— and upon the intermediate portion of this shaft is loosely mounted a roller —12— overlying the adjacent portion of the pipe —6— to hold the latter against undue vertical displacement from the bearing rollers —8—, said slots —9— being open at the top to permit the shaft —11— with the roller —12— to be easily and quickly removed or replaced.

A cotter pin—13—is inserted through apertures in the opposite walls of the slot to hold the shaft—11—against vertical displacement.

5 The opposite end walls as—7—of the slot—7—are rounded outwardly and are disposed equal distances from the transverse vertical center of the brackets of which they form a part for receiving and retaining the 10 hood—14—in its operative position.

These hoods may be made in separate units, one for the roller bearing of each pipe as shown in Figure 4, or may be made as 15 single units to cover the roller bearings for

two or more pipes as shown in Figure 1, but in each case the unit is preferably made of spring sheet metal in the form of an inverted box having its end walls provided with central vertical slots—15—opening 20

from the bottom upwardly to the top wall as—16—thereby dividing the box into opposite similar half sections connected only by the top wall—16—which is more or less resilient to permit the lower ends of the 25

box sections to yield laterally when placing the hood upon or removing it from the brackets in a manner presently described.

The opposite half sections or jaws of the hood—14—are provided with top, side and 30 end walls—17,—18—and—19,—the side and end walls being rigidly united at their upper ends to the top walls—17—which in turn are rigidly connected to each other by the resilient bridge—16.

35 The side walls—18—are provided with aligned openings—20—extending upwardly from the bottoms to points near the top walls—17—for receiving the signal operating pipes—6—and are of sufficient size to 40 avoid friction therewith.

The opposite walls of the upper portion of the slot—15—are preferably parallel and spaced apart a distance corresponding approximately to the width of the upper portions of the brackets—1—to allow the hoods to slide downwardly over the inner sides of the brackets at opposite ends of the rollers—8—and—12—while the opposite walls of the lower portion of the slot 45 are flared downwardly and laterally and are recessed at 15' to form concave seats which are frictionally engaged with the rounded end walls—7—on the adjacent sides of the brackets—1—for frictionally retaining the 50 hood in operative position upon the carriers. 55

The opposite walls of the lower ends of the slots—15—are beveled downwardly and outwardly at—21—and are normally spaced apart a distance somewhat less than 60 the distance between the outer edges of the rounded portions—7—and also a distance less than the distance between the concave seats—15—so that when the hoods are placed in operative position upon the carriers and pressed downwardly by hand the 65

beveled edges—21—will ride across the outer faces of the rounded portions—7—thereby springing the opposite halves of the hood apart against the action of the spring—16—until the concave seats—15— are registered with the portions—7—whereupon the seats—15—will be spring-pressed against the rounded portions—7—to frictionally hold the hood in operative position against accidental upward displacement but permitting said hoods to be removed at will by upward displacement when desired.

In other words, the opposite end walls of the hoods are divided longitudinally from 80 bottom to top except that they are united by the spring yoke—16—so that the opposite halves of the hood constitute opposed jaws which are spring-pressed into engagement with the carrier when the hoods are 85 adjusted for use while the concave seats—15—cooperating with the rounded portions—7—serve to frictionally lock the hoods in operative position.

In Figures 1 to 4 inclusive the spring 90 yoke—16—connecting the upper ends of the opposite halves of the hood are formed integral with the top wall of the hood and thereby constitute a part thereof while in Figure 5 the yoke as—16'—is made of separate spring metal and secured by rivets—22—or other suitable fastening means to the top walls of the opposite halves of the hood to form a part of the top wall thereof.

In each of the modifications the top wall 100 of the hood is inclined upwardly from the side toward the center for the purpose of shedding water, snow and other foreign matter therefrom and thereby protecting the engaging parts between the pipe and carrier 105 against accumulations of rain, and other foreign matter and permitting the pipes and rollers to operate more freely under all weather conditions.

When the hood is used for protecting the 110 connections between a single pipe and its carrier the opposite end walls thereof are engaged with the rounded portions—7—of adjacent brackets—1—at opposite sides of the pipe but when the hood is used for protecting the carriers of two or more parallel pipes they are correspondingly elongated so that the end walls thereof may engage the brackets at the outer sides of the pipes nearest to the ends of the hood in 115 which case the side walls of the hood will be provided with a number of openings—20—.

What we claim is:

1. A hood for pipe carriers having top, side and end walls, two of the opposite walls 125 being divided vertically from bottom to top, the top wall extending across the division.

2. A hood for pipe carriers having top, side and end walls, two of the opposite walls being divided vertically from bottom to top, 130

the top wall extending across the division, the lower portions of the walls at opposite sides of the divisions being provided with concave seats for engaging portions of a pipe carrier.

3. A hood for pipe carriers of railway signal systems, said hood having top, side and end walls, two of the opposite walls being divided from bottom to top, the top wall being extended across the division, the lower portions of the walls at opposite sides of the division being provided with beveled edges to facilitate the placing of the hood upon the carriers.

15 4. A hood for pipe carriers for railway signal systems comprising an inverted box-like structure having two of its opposite walls provided with slots extending from the bottom to the top midway between the remaining two sides to form opposite half sections, the top wall extending across the slot for connecting said half sections.

20 5. A hood for pipe carriers for railway signal systems comprising an inverted box-like structure having two of its opposite walls provided with slots extending from the

bottom to the top midway between the remaining two sides to form opposite half sections, the top wall extending across the slot for connecting said half sections, the portions of the walls at opposite sides of the slots being provided with concave seats for frictionally engaging portions of the carrier. 30

6. A hood for pipe carriers for railway signal systems comprising an inverted box-like structure having two of its opposite walls provided with slots extending from the bottom to the top midway between the remaining two sides to form opposite half sections, the top wall extending across the slot for connecting said half sections, the portions of the walls at opposite sides of the slots being provided with concave seats for frictionally engaging portions of the carrier, the remaining walls being provided with slots extending from the bottom upwardly for receiving the pipes. 35 40 45

In witness whereof we have hereunto set our hands this seventh day of April, 1925.

WILLIAM F. BOSSERT.

JOHN C. EDWARDS.
